The ornamental design for an anchor, as shown and described.

DESCRIPTION

FIG. 1 is a perspective view of an anchor showing my new design;

FIG. 2 is a second perspective view;

FIG. 3 is a front elevation view;

FIG. 4 is a back elevation view;

FIG. 5 is a left-side elevation view;

FIG. 6 is a right-side elevation view;

FIG. 7 is a top plan view; and,

FIG. 8 is a bottom plan view.

The broken lines showing holes are included for the purpose of illustrating environmental structure and form no part of the claimed design.

The break lines shown in FIGS. 1-6 indicate a symbolic break in length. The appearance of any portion of the article between the break lines forms no part of the claimed design.
